(57) **CLAIM**

The ornamental design for electronic device having antenna, as shown and described.

DESCRIPTION

FIG. 1 is a front view of an electronic device having antenna in accordance with the present invention;

FIG. 2 is a rear view of the electronic device having antenna in FIG. 1;

FIG. 3 is a left side view thereof;

FIG. 4 is a right side view thereof;

FIG. 5 is a top view thereof; and,

FIG. 6 is a bottom view thereof.

The broken lines in the drawings represent unclaimed environment structure only and form no part of the claimed design. The dash-dot-dash lines represent the unclaimed boundary line only and form no part of the claim design. The dash-dot-dot-dash lines are used to show an isolated enlarged view only and form no part of the claim design. The article is not limited to the scale shown herein. As indicated in the title, the article of manufacture to which the ornamental design has been applied is an electronic device having an antenna. Examples of an electronic device are a computer, a portable or hand-held electronic device, a memory device, an RFID device, an NFC device, a communication device (e.g., cellular phone), a novelty item, a toy, and/or the like.
